Richard B. Brown
ATTORNEY.

UNITED STATES PATENT OFFICE

NATHAN UNGER, OF NEW YORK, N. Y.

ANNUNCIATOR

Application filed September 17, 1924. Serial No. 738,252.

This invention relates to annunciators and more particularly to a novel and improved apparatus the operation of which is positive and reliable.

5 The most important object of my invention is to provide for use in a burglar alarm or other protective system an annunciator, which operates to indicate the closing of an open circuit or the opening of a 10 closed circuit.

Another object of my invention is the construction of an annunciator which is operable by either a closed circuit or an open circuit to close another circuit.

15 To enable others skilled in the art to fully comprehend the underlying features of my invention, that they may embody the same in the various modifications in structure and relation contemplated, drawings depicting 20 a preferred form have been annexed as a part of this disclosure and in such drawings, similar reference characters denote corresponding parts throughout all the views, of which,

25 Figure 1 is a front view of an annunciator constructed in accordance with my invention.

Figure 2 is a view taken on the line 5—5 of Figure 1.

30 Figure 3 is a plan view of the annunciator shown in Figure 1.

Referring to the drawings in detail in which a master instrument is illustrated embodying the annunciator mechanism, numeral 29 designates a frame in the rear portion of which are mounted two relays indicated generally by the numeral 30, each comprising two coils 31, 31^a cooperating respectively with armatures 32, 32^a, the armature 32 being under tension of the spring 33 attached thereto and the opposite end of the spring connected to an adjusting screw 34. The two lower electromagnetic coils 31^a of an open circuit cooperate with the armature 32^a directly below the armature 32 of the closed circuit which armature 32 is operated by the two coils 31.

The armature 32 is attracted and is held under slight tension of the spring 33 so that 50 when the circuit is broken, the armature

will be released. In the open circuit, however, the armature 32^a will be attracted when the magnets 31^a are energized and the open circuit becomes closed. Referring particularly to Figure 2, it will be seen that each 55 armature is connected by a link 35 to a bent arm 36, each of said arms having a pin 37 in the end thereof, extending through a slot 38 of a sliding trip plate 39. The trip plate extends through a guide 40, secured to the 60 side wall 41 of the frame. A similar guide 42 is provided for the respective arms 36, it being noted that the sliding trip plate 39 is under slight tension of the small spring 43 connected to the guide 40. The sliding 65 plate is adapted to be moved inwardly and outwardly when the armature 32 is released or when the armature 32^a is attracted, in which instance the closed circuit and the 70 open circuit are independent of each other in affecting this operation. On the sliding trip plate, a lug or extension 44 is provided and is adapted to engage the lower end 45 of the bent arm 46, which arm is mounted on one end of a square shaft 47, said shaft 75 being adapted to oscillate or partially rotate between the sides 48 of an extension formed with the frame heretofore referred to.

Attached to the shaft 47 and movable therewith is a circuit closing annunciator 80 drop 49 which is provided with a knife switch blade 51, adapted to engage the forked contact 52 of a short rod 53, see Figure 2. The bevelled end 54 of the rod 53 is adapted to engage the spring catch or lock 55, mounted on the knife switch and below the annunciator drop 49, so that when the said drop is released by the arm 46 and completes a circuit, it causes an alarm. A finger piece 55^a permits the catch 55 to be 85 released manually to the full line position as indicated in Figure 2 and thus the sliding trip plate may be set after the alarm circuit has been broken. In connection with the annunciator drop, a signal lamp 56 in a socket 57 is provided so that it may be readily determined from suitable openings in a casting which master instrument has been operated.

Attached to the side of the frame 29 by 100

a bracket 60, is what I term a no current relay, the magnet 61 of which cooperates with an armature 62 to which a spring contact 63 is attached. The said contact 63 extends between adjusting screws 64, 64, of a support 66. The armature 62 is connected to a rod 67 by a spring 68 for the purpose of biasing the armature. A trouble relay is mounted on the frame on the opposite side of the no current relay and also comprises an electromagnet 76, armature 77, and spring contact arm 78, similar in construction with the mechanism just described in connection with the no current relay.

15 While I have illustrated and described my invention with some degree of particularity, I realize that in practice various alterations therein may be made. I therefore reserve the right and privilege of changing the form 20 of the details of construction or otherwise altering the arrangement of the correlated parts without departing from the spirit of the invention or the scope of the appended claims.

25 Having thus described my invention, what I claim as new and desire to secure by United States Letters Patent is:—

1. In an instrument of the class described, a plurality of relays each of which has two coils, an armature for each relay, a slide plate, links connecting said plate to each of said armatures whereby the plate will be moved upon operation of either of said relays, a circuit closing switch, a trip arm on said switch and a pin on said plate for engaging said arm, the pin being adapted to release said arm on a movement of said plate.

2. An instrument of the class described comprising a plurality of relays each of which has two coils, an independent armature for each relay, one of said armatures being normally attracted and the other armature normally unattracted, a movable plate connected to both of said armatures, a circuit closing switch adapted to be operated by a movement of said plate, a contact for releasable engagement with the switch, and a finger piece on the switch for permitting manual release thereof.

30 3. In an instrument of the class described, a plurality of relays, an independent armature for each relay, links connected to each armature, a sliding plate movable by the link connected to the actuated armature, a circuit closing switch, a pin on said plate for maintaining the switch open and said pin permitting said switch to close upon a sliding movement of said plate.

35 4. An instrument of the class described, a plurality of relays, an independent armature for each relay, links connected to each of the armatures, a sliding plate movable by the link connected to the actuated armature, a circuit closing switch, an extended arm connected to said switch, a projection on the

plate for releasing said arm when the said plate is actuated and means for locking said switch in its closed position.

5. An instrument of the class described comprising a plurality of relays, an independent armature for each relay, links connected to each of the armatures, a sliding plate movable by either of the links, a pivoted circuit closing switch, a retaining arm thereon, a pin on the plate, against which the retaining arm is set, whereby the arm is releasably held by the sliding element and means for automatically locking said switch when closed.

6. An instrument of the class described comprising a plurality of relays, an independent armature for each relay, links connected to each of the armatures, a sliding plate movable by either of the links, a pivoted switch, a retaining arm thereon, a pin on the plate against which the retaining arm is set whereby the arm is releasably held by the sliding plate, a catch for automatically locking said switch when closed and a finger knob on the switch for permitting manual release thereof.

In testimony whereof I affix my signature.
